INVENTOR:
Perle de Glass

UNITED STATES PATENT OFFICE.

PERLEY R. GLASS, OF BROOKLINE, MASSACHUSETTS, ASSIGNOR TO UNITED SHOE MACHINERY CORPORATION, OF PATERSON, NEW JERSEY, A CORPORATION OF NEW JERSEY.

HEEL-COVERING APPARATUS.

Application filed September 9, 1918. Serial No. 253,255.

To all whom it may concern:

Be it known that I, PERLEY R. GLASS, a citizen of the United States, residing at Brookline, in the county of Norfolk and 5 State of Massachusetts, have invented certain Improvements in Heel-Covering Apparatus, of which the following description, in connection with the accompanying drawings, is a specification, like reference characters on the drawings indicating like parts 10 in the several figures.

This invention relates to apparatus for covering the heels of shoes with flexible material, as leather or fabric, and more especially to apparatus adapted to apply covering to heels which have been secured to shoes.

As far as I am aware, operations of the character above outlined have been performed either wholly by a series of relatively slow manual operations or with apparatus requiring special attachments to the covering. By the apparatus of the present invention heels in place upon shoes are rapidly 25 and effectively covered with material in the form ordinarily provided and with little manual effort.

A feature of the invention includes means for preparing a shoe for the application of 30 the covering, together with means for forcing said covering into engagement with the shoe. In the particular embodiment of the invention herein disclosed there are two preparatory steps; one accomplished by 35 means for opening the rand crease into which the covering is to be forced and the other by means for smoothing the edge of the heel over which the covering is drawn.

A plurality of forcing means may also be 40 employed, one of these causing the covering material to enter the rand crease, drawing said material over the edge of the heel, and the other pressing it into contact with the edge.

45 A feature of the invention is also furnished by the preparing means, which have a portion for engagement with a heel and a flange arranged to enter the rand crease of the shoe to which the heel is secured. This 50 also applies to other elements of the apparatus, as to a portion of the means for forcing the heel covering into the rand crease and to the means for pressing the covering against the edge of the heel. The crease-entering flange may be provided with pro-

jections to facilitate the feeding of the work, the covering-forcing means being herein so shown.

A further feature of the invention is found in the forcing means which operates 60 on the covering. The mechanism which I have shown for the purpose of tucking the covering into the rand crease has a work-guiding member and a pressure member operating upon the heel covering adjacent 65 to the guiding member. The pressure or tucking member preferably has a reciprocatory movement, while the guiding member may yield to vary the projection of the tucking member beyond it. 70

As a feature of a machine embodying the foregoing preparing means and tucking means, and acting upon the work between the two, I preferably provide means for trimming said covering to leave a correct 75 uniform projection beyond the edge of the heel. In the trimming mechanism here illustrated there is a rotatable knife and a guard for contact with the heel to which the covering is to be applied, said covering passing between the knife and guard. I also prefer to have associated with the knife a gage co-operating with the rand crease of the shoe operated on to determine the width to which the edge of the covering is to be 80 trimmed, and there may be means provided for adjusting the relative position of the knife and either the guard or gage or both 85 these members.

I do not claim this trimming means in the 90 present application, however, since the same forms the subject-matter of a divisional application having Ser. No. 329,996, filed the 11th day of October, 1919.

In connection with the following description of one embodiment of the invention which I have chosen to illustrate in the accompanying drawings, other features will appear. 95

In these drawings,

Fig. 1 is a top plan view of the apparatus;

Fig. 2 is an end elevation looking from the left in Fig. 1;

Fig. 3 is a sectional detail on the line 3—3 of Fig. 2;

Fig. 4 is a similar view on the line 4—4 of Fig. 2;

Fig. 5 is a perspective view of the tucking mechanism with a portion broken away, and 110

Fig. 6 is a broken elevation of the trimming mechanism.

From an upright 10 adjustable vertically in a base standard 12 project three horizontal arms 14, 16, and 18, the first two being oppositely alined at the rear of the machine while that last named extends forwardly. Upon these arms the operating elements of the apparatus are carried, and these will be described in the order in which they act upon the work. Upon the arm 14 of the frame is a forwardly extending bracket 20, having fixed in it parallel to the arm a spindle 22. Rotatable upon the outer extremity 15 of this spindle and secured in place by a screw 24 is a work-preparing member 26. This I have shown as in the form of a roll, having a body portion 28 situated at the side toward the bracket 20 and an outer annular flange 30 perpendicular to the axis of the spindle. The periphery of the body and the flange converge toward one another, the angle between them preferably being substantially that between the outer portion of the heel to be operated upon and the heel seat end thereof. The portion 28 of the roll furnishes a rest over which the heel is guided by the operator, while the flange is of sufficient thickness and length to force open the rand crease so that it may readily receive the covering. In using this device the operator, resting the side of the heel near the breast against the under side of the portion 28 of the roll with the flange in the rand crease, runs the work beneath the roll until the opposite side of the breast is reached and the walls of the entire crease somewhat separated.

Journalized in the arms 14 and 16 is a shaft 32 rotated from a suitable source of power by a belt 34 co-operating with fast and loose pulleys 36. A belt shifter 38 mounted upon a bracket 40 from the frame enables the belt to be moved from one pulley to the other. Carried at the right hand extremity of this shaft 32 is mechanism for further preparing the heel for the reception of the covering. This consists of a beating member 42 having a body portion in the form of a roll 44 fixed upon the end of the shaft. About the periphery of the roll are undercut recesses to receive beating projections shown as consisting of small rolls 46 turning in the recesses between end plates 47 and 50, and having at the inner extremity of each an anti-friction ball 48 serving as a thrust bearing. The edge of the outer plate 50 extends beyond the face of the roll 44 to furnish a guide flange. The angular relation between this flange and the periphery of the roll 44 with its small rolls 46 is similar to that between the body and flange of the roll 26. That is, the inclination of the edge of the roll is such as to somewhat conform to the edge of a heel when the flange is inserted in

the rand crease. The operator applies the work to this roll 42 in the same manner as to the crease-opening roll, and, as the edge of the heel moves beneath it, the revolving rolls 46 beat out and smooth any roughness, giving an even surface over which to stretch the heel covering.

Upon the heel thus prepared the covering is cemented, leaving the edges projecting beyond the top and bottom. To give uniformity to the edge which is to enter the opened rand crease, it is trimmed by the following mechanism. At the forward end of the arm 18 is a transverse extension 52 in which is journaled a horizontal shaft 54 connected for rotation to the shaft 32 by belt gearing 56. Fast upon the left hand extremity of the shaft 54 is a circular knife 58 provided with a peripheral cutting edge. Carried upon the portion 52 of the arm 18 and surrounding the knife is a casing, having a body 60 closed at its outer side by a head 62. There is, however, at the lower forward portion of this casing an opening appearing at 64 in Fig. 2 of the drawings, through which the knife projects for co-operation with the work. Engaging the counter portion of the shoe operated on is a guard having a shank 66 secured to the cover 62 of the casing by a screw and slot connection 68 allowing its movement radially of the knife. Projecting from the shank, first outwardly in a horizontal direction and then downwardly and inwardly, is an arm 70 having at its lower end beneath the knife a laterally extended guard portion 72 curved to conform generally to the counter portion of a shoe and against which the cutting edge of the knife operates. The form of the arm permits the excess of material which is to be trimmed away from the covering to enter between the knife and guard, while the adjustment by means of the connection 68 enables the operator to bring the guard into proper relation to the knife as the latter is worn away through sharpening.

To aid the operator in trimming to a line parallel to the rand crease, there is shown mounted on the edge of the casing 60 a gage arm 74 secured in place by a screw 76 passing through a transverse slot at the upper end of the arm. This arm 74 extends with its lower enlarged end 78 adjacent to the inner side of the knife, it being adjusted by means of the screw 76 so that when the gage is in the rand crease the knife will trim the heel covering to a width giving sufficient projection to properly tuck into and be retained in the crease. To allow the operator to correctly follow the crease in trimming, I prefer to first mark its position upon the covering by running the work beneath the roll 26 in the same manner as when separating the walls of the crease, but more lightly. This causes the edge of the flange

30 to indent the covering in a line over the crease, so that the operator may easily follow it with the gage.

As the knife 58 becomes dull in use it may 5 be sharpened without removal from the apparatus by a grinding member forming a part thereof. This grinding member is furnished by an abrasive wheel 80 fast upon the lower end of a spindle 82, rotatable in 10 upper and lower arms 84 carried on a slide 86 movable on the portion 52 of the arm 18. Turning in the support at the end of the slide is a screw 87 threaded into said slide, by which the position of the grinding wheel 15 with relation to the edge of the knife may be varied. Fixed upon the spindle beneath the upper supporting arm is a pulley 88 connected by a belt 90 with a pulley 92 on the shaft 32. To control the rotation of the 20 grinding wheel the belt passes over a tightener furnished by a pulley 94 mounted on a lever 96 fulcrumed upon the extension 52. The lever has upon one arm a spring latch 98 engaging a notched segment 100 secured 25 to the extension. By this tightener the belt 90 may be placed under such tension as to rotate the spindle 82 and the grinding wheel, or the belt may be loosened so that wheel is not driven. The lower run of the belt is 30 preferably guided by a pulley 102 rotatably mounted on the arm 18. The grinding wheel is held normally out of contact with the knife by a helical spring 104 surrounding the spindle and interposed between the lower 35 bearing arm and the pulley 88. The spindle may be pressed down to bring the grinding wheel into engagement with the edge of the knife by a finger piece or head, 106, loosely mounted upon the upper extremity of the 40 spindle and retained in place thereon by a screw 108 extending into a circumferential groove in the spindle. An anti-friction ball 110 is shown (Fig. 3) interposed between the head and spindle so that the former may be 45 forced down by the operator without sharing in the rotation of the spindle.

After the edge of the covering has been trimmed, it is forced into the rand crease by a mechanism mounted upon the outer end 50 of the arm 14. To this arm is fixed a supporting casing 112 in which are formed vertical ways 114 and 116. In the ways 114 moves a slide 118 carrying rotatably upon its lower and outer face a guide wheel 120 of 55 the same general form and arranged to engage the work in the same manner as the roll 26. The flange of this roll 120 is, however, provided with projections 122 shown as of a regular scalloped or wave form. 60 These projections, by their engagement with the covering material, prevent its crawling or being displaced before the roll as the work is moved beneath it. The slide 118 is recessed at its inner side to receive a helical 65 spring 124 situated between the bottom of

the recess and a pin 126, extending horizontally from the front to the rear of the casing 112 and passing through a vertical slot 128 in the slide. This spring holds the slide and guide roll normally downward, yet permits it to rise under the pressure of the work to vary the projection into the rand crease of the tucking member which will now be described. Traveling in the way 116 is a slide 130 furnished with a socket 132 to receive the shank of the tucking member 134. This member consists of a vertical finger having a flat inner face movable in contact with the outer end of the roll 120. The lower extremity of the finger is reduced at 136 and lies in proximity to the edge of the flange of the guide wheel. The tucking finger is reciprocated by an eccentric 138 formed upon the end of the shaft 32 and joined by an eccentric rod 140 and pin 142 threaded into the rod to the upper end of the slide 130, in which the pin 142 turns. Starting the work at the breast of the heel with the body of the roll 120 contacting with the heel covering, as illustrated in Fig. 5 of 90 the drawing, and the flange starting the trimmed edge into the rand crease, the reciprocating finger forces the material smoothly and uniformly into the crease as the work travels beneath it, until the opposite side of the breast is reached.

To remove any irregularities of the covering at the edge of the heel it may be passed over a smoothing or finishing tool. This tool is mounted upon a bracket 144 100 projecting forwardly from the arm extension 52, it having a shank 146 fixed in a vertical opening in the bracket. This tool, as illustrated, has a body 148 square in horizontal section, and this at one side is provided with a portion formed with a curved end face 150. At one side of this face, here shown as at the left, is a depending flange 152. The flange is introduced into the rand crease and the work, with the covering applied to the heel and tucked into the crease, moved over the face 150 by short opposite strokes, this serving to press out projections which may have formed in the covering during the operation of tucking it into the 110 crease.

To sum up the operation of the apparatus, the rand crease of the heeled shoe S is opened by the action of the roll 26 to give the desired space for the admission of the 120 covering, and the heel edge adjacent to the crease is smoothed by the beating projections 46, thus preparing the work to receive the covering. Said covering C is then cemented upon the heel, is marked at e over the crease by the roll 26 and is trimmed parallel to this mark by the rotating knife 58. Finally this even projecting edge of the covering is tucked into the crease over the smooth edge of the heel by the reciprocating 125 130

ing finger 124 and the inequalities of the covering leveled by the smoothing surface 150. The application of the toplift and the finishing of the heel at the breast may be 5 performed in the usual manner.

Having described my invention, what I claim as new and desire to secure by Letters Patent of the United States is:

1. In a heel-covering apparatus, a member 10 having a frusto-conical guiding surface for engagement with a heel attached to a shoe and a working portion arranged to enter the rand crease of the shoe.
2. In a heel-covering apparatus, a rotatable member having a frusto-conical guiding surface for engagement with a heel attached to a shoe and a working flange arranged to enter the rand crease of the shoe.
3. In a heel-covering apparatus, a rotatable member having a frusto-conical guiding surface for engagement with a heel attached to a shoe and a flange arranged to enter the rand crease of the shoe and having fixed 20 projections.
4. In a heel-covering apparatus, a roll having a heel-engaging guide portion and a rand-crease-entering working flange having projections arranged to engage successive increments of the covering of a heel and 30 tuck them into the rand crease, the flange and periphery of the heel-engaging portion converging toward one another.
5. In a heel-covering apparatus, a roll having a heel-engaging portion and a rand-crease-entering flange provided at its edge 35 with fixed projections.
6. In a heel-covering apparatus, a member for guiding work held by an operator, and a pressure member operating upon the 40 covering adjacent to the guiding member, said members being constructed and arranged for co-operative action in tucking the covering of a heel into the rand crease of a shoe.
7. In a heel-covering apparatus, a member 45 for guiding work held by an operator arranged for contact with the covering, and a pressure member operating upon the covering adjacent to the guiding member, said members being constructed and arranged for co-operative action in tucking the covering of a heel into the rand crease of a shoe.
8. In a heel-covering apparatus, a member 55 for guiding work held by an operator, a movable pressure member operating upon the covering adjacent to the guiding member, and means for actuating the pressure member, said members being constructed and arranged for co-operative action in tucking 60 the covering of a heel into the rand crease of a shoe.
9. In a heel-covering apparatus, a member 65 for guiding work held by an operator, and a reciprocating pressure member operating upon the covering adjacent to the guiding

member, said members being constructed and arranged for co-operative action in tucking the covering of a heel into the rand crease of a shoe.

10. In an apparatus of the class described, 70 a rotatable work-guiding member, and a pressure member reciprocating across the face of the rotary member in a direction perpendicular to its axis of rotation.

11. In an apparatus of the class described, 75 a yieldable member for guiding work held by an operator, and a pressure member operating upon the work, adjacent to the guiding member, both of said members being constructed and arranged for independent 80 co-operative motion in the crease between the upper and the bottom of a shoe.

12. In an apparatus of the class described, 85 a rotary rand crease guide, and a pressure member arranged to enter the rand crease adjacent to the guide.

13. In an apparatus of the class described, 90 a rotary rand crease guide, a pressure member arranged to enter the rand crease adjacent to the guide, and means for reciprocating the member.

14. In a heel-covering apparatus, a guide 95 having a heel-engaging portion and a rand-crease-entering portion, and a covering-tucking member operating in proximity to the rand-crease-entering portion of the guide.

15. In a heel-covering apparatus, a guide 100 having a heel-engaging portion and a rand-crease-entering portion, and a covering-tucking member mounted to reciprocate over the rand-crease-entering portion of the guide.

16. In a heel-covering apparatus, a guide 105 having a heel-engaging portion and a rand-crease-entering portion provided with projections, and a covering-tucking member operating in proximity to the rand-crease-entering portion of the guide.

17. In an apparatus of the class described, 110 the combination with a support provided with ways, of a rotary guide member and a pressure member mounted in the ways, a power shaft rotatable in the support, and connections between the shaft and pressure member, both of said members being constructed and arranged to enter the crease between the upper and the bottom of a shoe.

18. In an apparatus of the class described, 115 the combination with a support provided with ways, of a rotary guide member and a pressure member mounted in the ways, a power shaft rotatable in the support, connections between the shaft and pressure member, and a spring acting to force the guide member toward the extremity of the pressure member, both of said members being constructed and arranged to enter the crease between the upper and the bottom of a shoe.

19. In an apparatus of the class described, 120

the combination with a support provided with ways, of slides mounted in the ways, a tucking member fixed to one of the slides, a guide roll rotatable upon another slide and

5 having one of its faces in proximity to the tucking member, a power shaft, and connections between the shaft and pressure-member slide, to reciprocate the pressure member in a direction perpendicular to the axis of

10 rotation of the guide roll.

20. In an apparatus of the class described, the combination with a support provided with ways, of slides mounted in the ways, a tucking member fixed to one of the slides, a

15 guide roll rotatable upon another slide and having one of its faces parallel to and in close proximity to the tucking member, a spring interposed between the guide-roll slide and the support, a power shaft, and

20 connections between the shaft and pressure-member slide.

21. In a heel covering apparatus, the combination of a rotatable work guiding member having a heel engaging portion and a

25 rand-crease-entering flange, a flat pressure member adjacent the guiding member and parallel to the flange thereof, and means for

reciprocating said pressure member.

22. In a mechanism for covering heels attached to shoes, a tucking member compris-

ing a flat, blunt edged device adapted to force the heel covering into the rand crease of a shoe, means for reciprocating said device, and means to guide a shoe and an attached heel thereto.

35

23. In a mechanism for covering heels attached to shoes, a tucking device reciprocably mounted for forcing the heel covering into the rand crease of a shoe, mechanism for reciprocating said device, and a support

40

for said device and mechanism to permit the presentation of a shoe having an attached partly-covered heel and with its rand-crease in position to be entered by said device as described.

45

24. A machine for use in operating on shoes having partially covered heels attached thereto and comprising, in combination, tucking means, a rotary shaft, connections therebetween to actuate said means to force the margins of the heel coverings into the rand creases of the shoes, and a support

50

for said means and said connections permitting the presentation of the rand crease of a shoe to said means without obstructing the manipulation of the shoe.

55

In testimony whereof I have signed my name to this specification.

PERLEY R. GLASS.
